UNITED STATES PATENT OFFICE.

WATSON S. LENNON, OF HARDINSBURG, KENTUCKY.

CAR-COUPING.

SPECIFICATION forming part of Letters Patent No. 363,474, dated May 24, 1887.

Application filed March 7, 1887. Serial No. 230,039. (No model.)

To all whom it may concern:

Be it known that I, WATSON S. LENNON, of Hardinsburg, in the county of Breckinridge, State of Kentucky, have invented a new and Improved Car-Coupling, of which the following is a specification.

This improved coupling is one of the class which couple automatically when two cars come together, and in which the cars can be uncoupled from the sides and top. The two ends of each car are provided with a portion of the coupling device, the mechanism at each end being different, but adapted to co-operate with mechanism such as is at the opposite end on an adjacent car. The mechanism at one end consists in a draw-bar recessed at both sides and a pivoted coupling-plate carrying two coupling-pins, one for each recess. When the cars are to be coupled, the lower ends of the coupling-pins are held elevated by resting upon a spring-actuated buffering-slide. The co-operating coupling device on the adjacent car consists of two curved links pivoted on opposite sides of and within the draw-head, so as to turn in a horizontal plane, and each link has in its outer end an elongated curved slot. The inner ends of these links (which stand normally at an angle to the axis of the draw-bar) are connected to a spring-actuated buffering-slide. When the two ends of the cars come together, the buffering-slides come in contact with the draw-heads of the opposite car and are pressed inward. This movement of one slide releases the coupling-pins, which thereupon fall into the recesses of the draw-head, whereas the movement of the opposite slide swings the slotted pivoted links into the recesses of the opposite draw-head, so that when the coupling-pins descend they enter the slots in said links, thus coupling the cars. The uncoupling is effected from the sides and top by means of a system of cords and pulleys which lift the coupling-plate, and with it the pins. When the pins are released from the slotted links, the latter are thrown open by the spring-actuated slide, to which they are attached, thus permitting the cars to separate without touching them. When the coupling-pins are lifted, the spring-actuated slide co-operating therewith moves forward beneath the pins, holding them up in position for the next coupling.

This improved coupling is shown in the accompanying drawings, in which—

Figure 1 is an end view of a box freight-car provided with the coupling-pin portion of the improved coupling. Fig. 2 is a bottom view of the draw-head thereof. Fig. 3 is a central vertical longitudinal section of both portions of the coupling, and Fig. 4 is a view showing the coupling-pin portion in plan and the link portion in horizontal section.

The draw-heads A of both portions are similar, and are arranged with cushioning-springs a, in a well-known manner, the draw-heads having a limited sliding movement between suitable guides, (indicated at b.) The draw-head of the coupling-pin portion is cut away to form recesses B B on both sides, the draw-head presenting on its front face a solid vertical portion or post, c, and horizontal pieces or bars d d. The recesses B B communicate with each other in the rear of the central face-post, c.

Pivoted to the draw-head, within a recess on the upper part thereof, is the coupling-plate C, which carries on its forward edge and on its bottom side the two coupling-pins D D. These coupling-pins move in and through apertures e e in the top of the draw-head, communicating with the recesses B B.

The spring-actuated buffering-slide, which holds the coupling-pins elevated when the cars are to be coupled, is constructed as follows: It consists of two sliding bars, E E, located beneath the draw-head, and held normally forward by springs F F, with their buffer-heads G G projecting beyond the draw-head. The bars E E extend through apertures in the bottom horizontal face-bar, d, of the draw-head, and the latter is provided with recesses f f, into which the buffer-heads G G enter when encountered by the opposite draw-head. At their rear ends the bars E E are secured to vertical rods H H, which extend through and slide in elongated slots g g in the draw-head. The upper ends of these rods are secured to a cross-plate, I, which slides in a recess, h, in the upper side of the draw-head. This cross-plate has two horizontal bars, J J, which extend forward in longitudinal recesses in the draw-head to the apertures e e, through which the coupling-pins pass. When the coupling-pins are raised clear of the apertures, the bars J J are moved for-

ward across the same by the springs F F, thus holding the coupling-pins raised.

The draw-head A of the adjacent car has an interior recess, K, in which slides a block, L. This sliding block is carried by a guide-rod, M, which carries on its front end a buffer-head, N, which projects beyond the draw-head, and which fits within a recess, i, in the draw-head when encountered by the vertical post c of the opposite draw-head. The rear end of the guide-rod M is surrounded by a coiled spring, P, which holds the slide L normally forward.

Pivoted within the draw-head so as to swing horizontally are the curved coupling-links O O, having curved elongated slots m m in their outer ends. The inner ends of the links are connected preferably by coiled springs s s to the slide L. The forward end of the slide L is curved, so that when the slide is pressed normally forward by the spring P it comes in contact with the links and throws the same out, as shown in Fig. 4. This position of the links is their normal one when the cars are to be coupled.

When, now, the opposite draw-heads come together, the buffer-heads G G N of the two slides are encountered by the draw-heads, thus moving in both slides. The inward movement of slide L swings the outer slotted ends of the links O O into the recesses B B of the opposite draw-head. At the same time the inward movement of the buffer-heads G G releases bars J J from the coupling-pins D D, permitting them to descend into the slots m m, and thus couple the cars.

To lift the coupling-plate C and so uncouple the cars, the plate is connected by a cord, rope, or chain, Q, to a ring, R, to which three other cords, ropes, or chains, S S T, are connected. The ropes S S pass upward over sheaves U U, and thence down through staples V V at the sides of the car. The third rope, T, passes directly through a staple, V, at the top of the car. Each rope has at its outer end a manipulating ring or loop, W.

A cord or chain, X, attached at opposite

ends to the draw-head and coupling-plate, limits the movement of the latter.

The links O O are held in position by coiled springs t t, interposed between them and the draw-head.

I claim as my invention—

1. In a car-coupling, a draw-head having side recesses therein and two coupling-pins, one for each recess, in combination with the adjacent draw-head having two links pivoted on opposite sides thereto, so as to swing in a horizontal plane, said links having slots in their outer ends, substantially as set forth.

2. In a car-coupling, a draw-head having side recesses therein, a coupling-plate pivoted thereto, and two coupling-pins attached to said plate, in combination with the adjacent draw-head having two links pivoted on opposite sides thereto, so as to swing in a horizontal plane, said links having slots in their outer ends, substantially as set forth.

3. In a car-coupling, a draw-head having side recesses therein, a coupling-plate pivoted thereto, two coupling-pins attached to said plate, and a spring-actuated buffering-slide operated by encountering the draw-head of the adjacent car, said slide holding said coupling-pins in an elevated position, in combination with the draw-head of the adjacent car having two links pivoted thereto, said links having slots in their outer ends, and a spring-actuated buffering-slide, to which said links are connected, said slide being operated to close the links by encountering the draw-head of the adjacent car, substantially as set forth.

4. The coupling-plate and the limiting-chain X, connected at opposite ends to said plate and the draw-head, in combination with ring R, ropes Q, S S, and T, sheaves U U, and staples V V, substantially as set forth.

In testimony whereof I affix my signature in presence of two witnesses.

WATSON S. LENNON.
